Attorney

UNITED STATES PATENT OFFICE.

CLARENCE E. CHASE, OF HARLAN, KENTUCKY.

ARCH SUPPORTER.

1,406,957.

Specification of Letters Patent. Patented Feb. 14, 1922.

Application filed April 7, 1921. Serial No. 459,215.

To all whom it may concern:

Be it known that I, CLARENCE E. CHASE, a citizen of the United States, residing at Harlan, in the county of Harlan and State 5 of Kentucky, have invented certain new and useful Improvements in Arch Supporters, of which the following is a specification, reference being had therein to the accompanying drawings.

10 This invention relates to arch supporters and has for an object to provide a supporter presenting physical novelty in relation to ventilating the foot of the user.

15 A further object of the invention is to provide an arch supporter which in addition to properly supporting the foot of the user will generate galvanic current for acting upon the foot.

20 A further object of the invention is to provide an arch supporter having a combination of metals of different electrostatic properties, whereby a galvanic current is produced by the action of the acids of perspiration thereon.

25 With these and other objects in view the invention comprises certain novel parts, elements, combinations, functions and attributes as will be hereinafter more fully described and claimed.

30 In the drawings:

Figure 1 is a view of the improved support in top plan, parts being broken away to show the internal construction;

35 Figure 2 is a longitudinal sectional view through the arch supporter, as indicated by line 2—2 of Figure 1;

Figure 3 is a transverse sectional view through the supporter as indicated by line 3—3 of Figure 1, and

40 Figure 4 is a perspective view of the several metallic parts which are combined within the casing.

Like characters of reference indicate corresponding parts throughout the several 45 views.

The present invention is a supporter to be placed within a shoe and having a yielding curvature for engaging under and supporting the arch of the foot. In the present 50 instance, the device comprises a casing preferably made of leather having an under sheet 10 and a top sheet 11. Between the two sheets a plurality of metallic members are inserted comprising one or more springs 55 12 and a zinc plate 13. The springs 12 will vary according to the weight of the person

for whom the device is constructed and while two have been shown, it is obvious that the device will be operative with more or less of such members. The several metallic plates 60 are similarly curved and provided with registering perforations 14. The laminated plates 12 and 13 will be inserted between the layers 10 and 11 of the covering and copper rivets 15 will be inserted through the openings 14 and through the cover members 11 and 12 and upset upon both sides or otherwise to maintain the said plates in superposed relation and between the covering members. A row of stitching 16 will be 65 formed around the plates 12 and 13 as nearly adjacent the edges of such plates as convenient to assist in holding said plates against movement between the layers 10 and 11.

A bowed extension 17 will be provided 75 curved upwardly, as indicated, to form a curved flange for the support of the inside of the arch of the foot, and the two layers 10 and 11, when combined in such integral structure by cement or other adhesive material, will be skived at the edges, as indicated at 18, such skiving being necessary only at the forward end and at the side of the flange.

A plurality of perforations 19 are preferably formed through the heel portion of 85 the supporter and other perforations 20 alongside the springs, forming communication between the top of the supporter and the space under the springs.

The curvature of the springs, as indicated 90 at Figures 2 and 4 is only shown as indicative of curvature and not as indicating the necessary curvature of the device, the metal parts being curved as may be required to fit the individual feet. The flange 17 likewise 95 will be curved or will curve itself more or less to correspond to the shape of the shoe and the foot. In other words, the device is intended to be shaped to the foot of the wearer and the requirements of curvature of 100 the arch, and anything herein shown or described as to outline of curvature is intended as no limitation upon the invention.

It is obvious that at each step of the 105 wearer the metal parts 12 and 13 will be depressed, reducing the space beneath the curved portion and pumping air through the perforations 19 and 20 to ventilate the foot. Also the copper rivets 15 extending up to and flush with the upper surface of the 110 sheet 11 will come in direct contact with the foot or the hosiery, which will be moistened

by the perspiration of the foot. Perspiration being of acid nature will act upon the copper rivets 15 to set up a galvanic current by reason of the engagement of the copper rivets 15 with the zinc plate 13.

What I claim to be new is:

The combination of a resilient arch support composed of a plurality of springs and a battery and a covering common to both 10 said members, said battery including a plu-

rality of rivets adapted to hold all said members together and to function as a metallic electrolytic element in said battery.

In testimony whereof I hereunto affix my signature in presence of two witnesses.

CLARENCE E. CHASE.

Witnesses:

W. D. RAGSDALE,
E. A. TAUG.
